BENJAMIN H. FREEDMAN, OF NEW YORK, N. Y., ASSIGNOR TO HUDSON HOLDING CORPORATION, OF NEW YORK, N. Y., A CORPORATION OF DELAWARE

MATCH PACKAGE

Application filed April 23, 1930. Serial No. 446,493.

This invention relates to a match package of the "book" type, such as is shown in my co-pending application for patent, Serial No. 442,753 filed April 9, 1930.

5 The object of this invention is to provide an improvement on the type of package shown therein and to produce a package in which the possibility of the matches in the package being accidentally ignited is entirely avoided.

10 It is well known that in match packages of the book type in use at the present time, the abrasive strip used for the striking of the matches is located on the infolded end of the package wrapper on the front of the pack-

15 age. The location of this strip of abrasive material is such that a match can be struck regardless of whether the package is open or closed with the result that many accidents have occurred by inadvertent ignition of the

20 entire package of matches, causing the manufacturers of book matches in use at the present time to warn the user by means of a notice on the package to close the package before striking a match. Attempts have been

25 made to devise improvements on the present day type of match book, such improvements consisting in placing the abrasive strip in various other positions on the package covering and on the closure flap. Many of these

30 other constructions have been impractical by reason of the fact that when the package is hastily thrust in the pocket, the cover flap sometimes becomes inadvertently tucked be-

35 hind the match strip, thus bringing the abrasive strip in actual contact with the match heads. A slight rubbing therefore, of the abrasive strip against the match heads can in such case cause the entire package to be ignited in the pocket.

The primary object therefore, of this invention is to provide a match book which will avoid the injurious possibilities heretofore mentioned and in which the abrasive strip is 45 so positioned with regard to the matches in the package that the same cannot under any possibility be brought into physical contact with the match heads regardless of any distortion or folding of the cover flap on which 50 the abrasive strip is provided.

Reference is to be had to the accompanying drawing, forming a part hereof in which

Figure 1 is a plan view of a match package made in accordance with my invention and showing the package in an open position; 55

Figure 2 is a perspective view of the closed package; and

Figure 3 is a plan view of the package showing the cover flap distorted and demonstrating the possibility of the abrasive strip 60 coming in contact with the match heads.

Throughout the various views of the drawing, similar reference characters designate similar parts.

In the embodiment of my invention disclosed in the accompanying drawing, 1 indicates the elongated strip of paper from which the package covering is formed. This strip has one of its ends inturned to form a flap 2 and this part 2 acts as a binding means for 70 holding the match strip 3 within the package.

The match strip 3 is held under the inturned flap 2 by means of a wing 4 provided along one edge of the strip, which wing extends parallel to the axis of the strip 3 and 75 projects from one of the sides thereof and lies beneath the inturned flap 2.

The fastening staple 5 extends through the flap 2, through the wing 4 on the match strip 3 and through the body portion 1 of 80 the paper covering, thus securely holding the match strip 3 in position.

A supplemental fastening means for holding the match strip to the cover 1 consists of an additional staple 6 which extends through 85 the match strip and through the cover 1. This staple 6 is located at right angles to the staple 5 and it passes through a narrow end portion 7 located along the bases of the matches in the strip. The staple 6 is preferably located adjacent the side edge 8 of the match strip so that should the cover flap 9, which is formed as an integral part of the cover 1 become distorted and tucked behind the match strip, it can not enter for any great 90 distance behind said strip, being prevented from so doing by the staple 6.

The cover flap 9 is provided with an abrasive strip 10 which is located along one of its side edges. This abrasive striking strip 10 100

preferably begins at the transverse fold 11 formed in the cover member 1 and terminates at 12, leaving a space 13 between the termination 12 of the strip 10 and the end 14 of the 5 cover 9. The reason for terminating this striking strip 10 short of the edge 14 will be apparent from the showing of Figure 3. Here it will be seen that the cover flap 9 has become distorted by being diagonally folded 10 on the line 15 so that the abrasive strip 10 has assumed a position substantially parallel to the matches in the strip. It will be here seen that since the strip 10 terminates at 12 and leaves a space 13 free of abrasive material, and 15 that said space 13 is located in alignment with the match heads, no amount of distortion of the cover flap can bring any part of the striking surface 10 in contact with the match heads.

20 It will be seen from the foregoing that I have devised a package affording absolute safety to the user. The position of the striking strip 10 with respect to the match heads is such that the cover flap 10 must be closed 25 before a match is struck. When a match is struck, the flame therefrom is located at a position remote from the match heads and thus cannot inadvertently ignite the matches in the package. Additionally, should the 30 cover flap become opened in the pocket and folded over or distorted from its usual position, it will be seen that due to the location and form of the abrasive strip, it cannot under any circumstances contact with the 35 match heads to cause a rubbing action and consequent ignition of the package.

Having described my invention, what I claim is:

40 A match package having a cover, a match strip extending cross-wise on said cover and having portions of the cover folded over it, the match strip being secured at two of its edges to the cover, with one of the secured edges lying at right angles to the other secured edge, a striking surface on the cover 45 extending longitudinally of it, said striking surface having one of its narrower ends terminating short of the free end of the cover and being so proportioned that it cannot be 50 brought into contact with the heads of the matches by the inadvertent angular folding of the cover.

Signed at the city, county, and State of New York, this 22d day of April, 1930.

55 BENJAMIN H. FREEDMAN.
